MATRIX FILLER

Andrew W. Davis, Madison, Ill.

Application May 15, 1945, Serial No. 593,950

4 Claims. (Cl. 12—63)

1

This invention relates to machines designed for skiving counter stiffeners of shoes, the primary object of the invention being to provide fillers having recesses of various sizes, and designs, the fillers being constructed so that they may be readily removed and replaced, to the end that the machine may be readily converted for constructing counter stiffener blanks of various sizes and designs, without the necessity of removing the matrix and replacing it with a matrix of a different size or design, thereby reducing the time period for converting the machine, to a minimum.

Another object of the invention is to provide a sectional matrix filler which when positioned on the matrix roll, will be securely held against displacement.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings

Figure 1 is an elevational view of a counter stiffener forming machine, illustrating a matrix filler, constructed in accordance with the invention, as positioned on the matrix roll thereof.

Figure 2 is a plan view thereof.

Figure 3 is a vertical sectional view through the machine.

Figure 4 is a perspective view illustrating the matrix roll sections as separated, and one of the filler sections used on the matrix roll.

Referring to the drawings in detail, the reference character 5 designates the table of a counter stiffener skiving machine, which is provided with an opening through which the feed roll 6 extends, the feed roll being rotated by suitable means not shown, whereby the counter stiffeners are fed through the machine.

The reference character 7 indicates the knife holder block, the fixed knife supported thereby, being indicated by the reference character 8, the knife being adjustable by means of the set screw 9 which is shown as extended into a threaded opening formed in the knife holder block 7, the main portion of the screw being disposed within the elongated opening 10 formed in the fixed knife 8.

The matrix roll is indicated by the reference character 11, and is mounted on the shaft 12, the matrix roll being provided with flanges 13

2

which are disposed directly opposite to each other, the flanges having cut-out portions 14 providing shoulders 15 adjacent to the ends thereof.

The matrix fillers embody semicircular members 16 which are constructed of suitable material, preferably plastic material, the members 16 being curved so that they will accurately fit the curvature of the matrix roll 11. As clearly shown by Fig. 4 of the drawings, one end of each matrix filler section 16 is formed with cut-out portions adjacent to one of its ends, providing an extension 17, the extensions 17 of the sections of the matrix filler, being positioned within the cut-out portions 14 of the matrix roll. The edges of the matrix filler sections are beveled, as shown by Fig. 4 of the drawings, and these beveled edges are adapted to cooperate with the beveled surfaces of the disks 18 and 19. The disk 18 is secured to the shaft 12, and when the matrix fillers are positioned, one end of each filler section is positioned so that it contacts with the beveled surface of the disk 18. The disk 19 is now slid into position over the opposite beveled edges of the sections of the fillers, and the nuts 20 are operated to force the disk 19 into gripping relation with the matrix filler sections. Thus it will be seen that due to this construction, the filler sections may be readily and easily removed or positioned. While I have shown and described the disk 18 as attached to the shaft 12, it is to be understood that the disk may, if desired, be constructed as an integral part of shaft 12.

It will of course be understood that the surface of the matrix filler sections are ground out to form recesses indicated at 21, to fit various sizes and designs of counter stiffeners thereby permitting the counter to move into the recesses which are formed to skive the desired portion of the counter stiffeners.

Should it be desired to remove the matrix fillers and replace them with fillers having recesses for skiving counter stiffener blanks of a larger or smaller size or design, the filler blocks may be readily removed and replaced with filler blocks which will form the required size of stiffener blank, eliminating the necessity of replacing the entire matrix roll, to make the change.

From the foregoing it is believed that due to the construction shown and described, the utility of applicant's invention will be apparent, and that a further detailed disclosure as to the use of the device is unnecessary.

What is claimed is:

1. The combination with a matrix roll and matrix roll shaft of a counter stiffener skiving

machine, of a matrix filler comprising wide semi-circular filler sections, adapted to fit around the matrix roll, said matrix roll having cut-out portions, extensions on the ends of the filler sections adapted to fit into the cut-out portions of the matrix roll, and disks fitted on the matrix roll shaft adapted to engage said filler sections, securing the filler sections on the matrix roll.

2. The combination with a matrix roll and matrix roll shaft of a counter stiffener skiving machine, of a matrix filler comprising wide semi-circular filler sections, adapted to fit around the matrix roll, a stationary disk mounted on the shaft and having a concaved surface, said filler sections having beveled edges adapted to fit into the concaved surface of the stationary disk, and a movable disk having a concaved surface adapted to fit over the opposite beveled edge of the matrix filler, securing the matrix filler sections on the matrix roll.

3. The combination with a matrix roll and matrix roll shaft of a counter stiffener skiving machine, of a matrix filler comprising wide semi-circular filler sections, means for securing the

ends of the sections to the matrix roll, the edges of the filler sections being beveled, a stationary disk having a concaved surface fitted on the shaft and adapted to fit over the beveled edges of the

5 filler sections, at one side of the filler sections, a movable disk having a concaved surface adapted to fit over the opposite side edges of the filler sections, and a nut on the matrix roll shaft adapted to engage the movable disk, securing the movable disk in engagement with the filler sections.

10 4. The combination with a matrix roll and matrix roll shaft of a counter stiffener skiving machine, of a matrix filler comprising wide semi-circular sections adapted to fit over the matrix, shoulders on the matrix, extensions at the ends of the matrix filler sections adapted to engage the shoulders of the matrix, securing the filler sections against lateral movement with respect to the matrix, and disks having concaved surfaces adapted to embrace the ends of the filler sections, securing the filler sections on the matrix roll.
